UNITED STATES PATENT OFFICE.

JOSEPH W. JACKSON, OF BROOKLYN, NEW YORK, ASSIGNOR TO HARRY PERLMUTTER, OF BROOKLYN, NEW YORK.

DESIGN FOR A BABY-CARRIAGE TOP.

Application filed October 31, 1928. Serial No. 28,635. Term of patent 14 years.

To all whom it may concern:

Be it known that I, JOSEPH W. JACKSON, a citizen of the United States of America, and residing at Brooklyn, in the county of Kings, State of New York, have invented a new, original, and ornamental Design for Baby-Carriage Tops, of which the following is a specification, reference being had to the accompanying drawing, forming part thereof.

I claim:

The ornamental design for a baby carriage top, as shown.

JOSEPH W. JACKSON.
